UNITED STATES PATENT OFFICE.

BENJOHN F. CRISENBERRY, OF KOKOMO, INDIANA.

FEED VALVE.

Application filed October 24, 1921. Serial No. 509,919.

To all whom it may concern:

Be it known that I, BENJOHN F. CRISENBERRY, a citizen of the United States, residing at Kokomo, in the county of Howard and State of Indiana, have invented a new and useful Feed Valve, of which the following is a specification.

This invention aims to provide a simple but efficient means whereby a drop-by-drop feed may be provided, at places where lubrication is desired, or elsewhere.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings:—

Figure 1 shows in vertical transverse section, a device constructed in accordance with the invention, parts appearing in elevation; Figure 2 is a cross section on the line 2—2 of Figure 1; Figure 3 is a cross section on the line 3—3 of Figure 1.

The numeral 1 denotes an oil tank. The numeral 2 marks a combined oil reservoir and float chamber, which is a composite structure, the same including a base 3 and a lid 4, the base 3 being threaded at 5 into the lid 4, the members 4 and 3 having cooperating flanges 6, between which is located a packing 7, affording a tight joint, the base 3 being removable to give access to the interior of the reservoir and chamber 2. At its lower end, the base 3 carries a nozzle 8 having a bore 9 leading upwardly to a conical seat 10 in the upper end of the nozzle. The upper end of the nozzle projects as at 11 above the bottom of the base 3. The lid 4 is supplied with a reduced neck 12. The neck 12 is mounted in the bottom of the oil tank 1 and is secured thereto in any suitable way, as shown at 14.

The numeral 15 designates a regulating stem including a tubular body 16 mounted to slide in a collar 17 on the top of the oil tank 1, the body carrying a turning head 18 provided with a vent 19. At its lower end, the

body 16 carries a foot 20 of appreciable thickness, the foot being threaded at 21 into the neck 12. The foot 20 is supplied with a reduced opening 22 leading to an inverted conical seat 23 which is formed in the foot. The body 16 has a circumscribing recess 24 in which filtering material 25 may be located, the member 16 having perforations 26, located in the base of the recess 24, the filtering material 25 extending across the openings. An air conduit 27 is mounted at its lower end in the foot 20 of the regulating stem 15 and extends upwardly, to a point adjacent to the turning head 18, and well above any level which the oil can possibly attain in the body 16.

A float 28, preferably hollow, is located in the float chamber 2 and carries a valve rod 29 having a pointed lower end 30 cooperating with the seat 10, the valve rod being provided with a pointed upper end 31 cooperating with the seat 23.

In practical operation, oil enters the reservoir 2 from the oil tank 1, through the filtering material 25 and through the openings 26, the oil flowing through the opening 22 in the foot 20, and through the seat 23, the oil leaving by way of the seat 10 and the bore 9. Responding to gravity, the float 28 moves downwardly, the end 30 of the valve rod 29 closing on the seat 10. Buoyed upwardly by the oil delivered drop by drop into the reservoir 2, the float 28 moves upwardly, the end 31 of the valve rod 29 operating with the seat 23. Thus, a drop-by-drop feed through the bore 9 is secured. The vertical movement of the float 28 and the valve rod 29 may be adjusted by raising or lowering the regulating stem 15, it being observed that the lower end or foot 20 of the stem is threaded at 21 into the neck 12. Sediment finding its way into the base 3 of the reservoir 2 will accumulate about the projecting portion 11 of the nozzle 8 and will be prevented from passing into the bore 9.

Air can enter the float chamber 2 by way of the conduit 27 and the vent 19, and, therefore, the float 28 will operate independently of any conditions which might arise if the float were called upon to operate in vacuo. The threaded joint at 21 is so located that there can be no leakage through the joint, to a point external to the device. Owing to the fact that the filtering material 25 is located in the circumscribing recess 24, the

regulating stem 15 may be withdrawn, upwardly without difficulty, through the collar 17.

The device is so constructed that it will 5 secure a steady flow or feed of the lubricant. The vertical movement of the float 28 and the valve at 29 serves to facilitate the flow of oil and to prevent the accumulation of a gummy film on the ends of the valve rod 10 or upon the seats 23 and 10.

Having thus described the invention, what is claimed is:—

1. A combined oil reservoir and float 15 chamber including a cup-shaped base and a dome-shaped lid screwed one into the other, and having cooperating flanges to abut when the parts are assembled, said lid having a central opening with an internally threaded 20 collar surrounding it, a tubular stem having a foot threaded in said collar and provided with a central opening flared outwardly, said base having a bore extending centrally therethrough, and flared inwardly, a float 25 in said chamber having stems extending from its opposite faces and provided with cone-shaped valves to fit the seats formed in said foot and base, said tubular member being adjustable to control the opening in the base.

2. A combined oil reservoir and float 30 chamber including a cup-shaped base and a dome-shaped lid screwed one into the other, and having cooperating flanges to abut when the parts are assembled, said lid having a central opening with an internally threaded 35 collar surrounding it, a tubular stem having a foot threaded in said collar and provided with a central opening flared outwardly, said base having a bore extending centrally therethrough and flared inwardly, a float 40 in said chamber having stems extending from its opposite faces and provided with cone-shaped valves to fit the seats formed in said foot and base, said tubular member being adjustable to control the opening in the base, said foot having a pipe opening 45 therethrough and extending upwardly into said tube, said tubular stem being provided with a plurality of inlet openings and equipped with a removable apertured head. 50

In testimony that I claim the foregoing as my own, I have hereto affixed my signature in the presence of two witnesses.

BENJOHN F. CRISENBERRY.
